UNITED STATES PATENT OFFICE.

R. P. GILLETT, OF VIROQUA, WISCONSIN.

IMPROVEMENT IN WAGON-AXLES.

Specification forming part of Letters Patent No. **36,564**, dated September 30, 1862.

To all whom it may concern:

Be it known that I, R. P. GILLETT, of Viroqua, in the county of Bad Ax and State of Wisconsin, have invented a new and Improved Wagon-Axle; and I do hereby declare that the following is a full, clear, and exact description of the same, reference being had to the accompanying drawings, forming a part of this specification, in which—

Figure 1 represents a longitudinal vertical section of my invention. Fig. 2 is a plan or top view of the same.

Similar letters of reference in both views indicate corresponding parts.

To enable those skilled in the art to make and use my invention, I will proceed to describe it with reference to the drawings.

The axle A is made of iron or steel, or of wood with iron bands around it, and it is provided with a shoulder, a, in the ordinary manner. That part of the axle on which the wheel revolves is covered with a coating, B, of Babbitt metal or other similar composition from three-sixteenths to a quarter of an inch in thickness. This coating is put on in the following manner: the iron to be first washed with a solution of muriatic acid, zinc, and sal-ammoniac, then the axle to be placed in a mold made for that purpose, and the heated metal poured in around it, when it will adhere to the iron and become completely solid.

The coating B extends up on the inside of the shoulder a, forming a shoulder, b, which is cast hollow, with a cavity, c, sufficiently large to hold from one-half to a gill of oil, with an orifice or aperture, d, at the top, where the oil can be poured in, and then corked up, so that it is not thrown out through the motions of the vehicle. A small channel, e, extends

from the cavity c along on the top of the axle to the aperture f, where it will be constantly oozing out, and by the action of the wheel when in motion it (the oil) will be carried around and over the whole surface of the axle. By these means the axle is constantly lubricated and kept free from heating, however long and fast it may be run, the quantity of oil emitted through the aperture f being so small that there can be no chance for it to gum and thereby close up the oil-channel e. If it should be found, however, that the oil passes out too rapidly, a small piece of wick may be passed through the channel e, which will permit of the oil oozing out at the aperture f sufficiently for the lubricating of the axle, as above stated.

This improvement may be applied to wooden axles as well as to such made of iron simply by placing two bands of iron around coated with Babbitt metal, in the same manner as above described—one at the shoulder and one at the end of the axle.

Should the coating of Babbitt metal or other composition ever become worn, it can be renewed by the same process without taking the axle off from the vehicle, and when completed it will be just as good again as new.

Having thus fully described my invention, what I claim as new, and desire to secure by Letters Patent, is—

Having the axle covered with Babbitt metal, with an oil-reservoir made in such metal, all as herein set forth and described.

R. P. GILLETT.
